AWNNG

Robert L. Moore, Denver, Colo.

Application June 2, 1952, Serial No. 19,991

Term of patent 14 years

(Cl. D21—6)

To all whom it may concern:

Be it known that I, Robert L. Moore, a citizen of the United States of America, residing in Denver, in the county of Denver and State of Colorado, have invented a new, original, and ornamental Design for an Awning, of which the following is a specification, reference being had to the accompanying drawing, forming a part hereof.

In the drawing:

Fig. 1 is a perspective view of an awning, showing my new design; and

Fig. 2 is a transverse section therethrough looking toward the edge thereof.

I claim:

The ornamental design for an awning, as shown.

ROBERT L. MOORE.
